(57) **CLAIM**

The ornamental design for a calculator with port and cover, as shown and described.

DESCRIPTION

FIG. 1 is a front, left, top perspective view of a calculator with port and cover;

FIG. 2 is a back, left, bottom perspective view of a calculator with port and cover;

FIG. 3 is a front elevational view thereof, shown with the cover removed for ease of illustration;

FIG. 4 is a right side elevational view thereof;

FIG. 5 is a left side elevational view thereof;

FIG. 6 is a rear elevational view thereof;

FIG. 7 is a front, left perspective view of a calculator with port and cover, showing only the cover portion for ease of illustration;

FIG. 8 is a front elevational view thereof;

FIG. 9 is a rear elevational view thereof;

FIG. 10 is a right side elevational view thereof, the left side elevational view being a mirror image thereof;

FIG. 11 is a back plan view thereof; and,

FIG. 12 is a top plan view thereof.
